UNITED STATES PATENT OFFICE.

EMIL PODSZUS, OF NEUKÖLLN, GERMANY.

ELECTRIC INCANDESCENT LAMP WITH GAS FILLING AND A HOLDER FOR THE INCANDESCENT WIRE.

1,234,691.

Specification of Letters Patent. Patented July 24, 1917.

Application filed November 13, 1914. Serial No. 871,984.

To all whom it may concern:

Be it known that I, EMIL PODSZUS, a subject of the German Emperor, residing at Neukölln, in the Kingdom of Prussia, German Empire, have invented certain new and useful Improvements in Electric Incandescent Lamps with Gas Filling and Holders for the Incandescent Wires, of which the following is a specification.

- 10 My invention relates to electrical gas lamps. If such lamps are to burn in any position, a large number of holders is required, which must be disposed in a comparatively small space. If these holders are 15 made of metal only, the economy of the lamp is greatly reduced, since, in order to secure sufficient stability, the holders must be made rather thick, on account of which considerable heat is lost.
- 20 My invention has for its object to so secure the incandescent filaments or holders that, on the one hand, such great losses in heat are avoided, while, on the other hand, the holders can be conveniently insulated from 25 each other. This object is obtained by the employment of insulating holders. Since several tungsten wires can be conveniently placed close together on the same holder, the 30 holders are subjected to great heat resulting in very high temperatures. Most materials 35 can not stand these high temperatures, especially since to the effects of these temperatures are still added the effects of the electric current, whereby, in combination with the gas, almost all materials are, in the end, decomposed.
- As materials best suited for my purpose, 40 have been found nitrogen compounds, nitrides, such as boron nitrid, and the like. Though these materials possess an extraordinary 45 insulating capacity, even at high temperatures, yet the electric current and the temperature, in time, cause changes, which finally lead to destruction. Since 50 these changes can, however, only consist in the separation of nitrogen which separation in an atmosphere of nitrogen is held up or compensated for, the employment of nitrides is of decisive advantage in electric gas 55 lamps, filled with nitrogen, or an atmosphere containing nitrogen in sufficient amount. In this case, a permanent insulation need contain only nitrogen sufficient to prevent decomposition. Ammonia can, there-

fore, be used, and consequently, boron nitrid, which is the most refractory nitrid, can even at very high temperatures be used as an insulating holder for the metal filaments, made of tungsten, or the like, there being 60 no danger that the holder will be affected regarding its properties by thermic or electric influences, even during long periods of use, if the surrounding atmosphere contains enough nitrogen that the decomposing 65 effects of the current or the temperature are counteracted. The pressure of the nitrogen need be only proportionately small, as the dissociation only at very high temperatures assumes considerable proportions. For preventing discharges of gas, however, it is desirable to make the pressure as high as possible. The amount of the nitrogen pressure in the lamp depends upon the nature and the 70 temperature of the nitrid used, and is determined thereby. The pressure of the gases otherwise present is determined by the well-known principles followed in the manufacture of electric gas lamps. Instead of 75 boron nitrid, also other refractory, non-conducting or poorly conducting nitrides, e. g. silicon, aluminum, magnesium, or the like, can be used.

As incandescent filament preferably tungsten is used, which is not affected by boron 85 nitrid at the temperatures referred to. One can use the boron nitrid as the core for a fine spiral, for a double spiral, as holder for short hooks, in the shape of small rods and plates, and one can increase the temperature 90 to over 2000° C., no decomposition or injurious decrease of its insulating capacity taking place.

An example is shown in the accompanying drawing, where a spiral of tungsten is 95 wound in zig-zag shape over two small thin rods *a*, made of boron nitrid, a considerable difference in potential existing between the points 1 and 2 of the glowing rod.

I claim as my invention:

1. A gas filled electric incandescent lamp, 100 containing a holder used as a support for highly heated metal filaments and made of a refractory insulating nitrid.
2. In a gas filled electric incandescent 105 lamp, a holder used as a support for highly heated metal filaments and made of a refractory insulating nitrid, in combination with an atmosphere containing nitrogen.
3. A gas filled electric incandescent lamp, 110

containing a holder used as a support for highly heated metal filaments and made of boron nitrid.

4. In a gas filled electric incandescent lamp, a holder used as a support for highly heated metal filaments and made of boron nitrid, in combination with an atmosphere containing nitrogen.

5. In a gas filled electric incandescent lamp, a holder used as a support for highly

heated metal filaments and made of boron nitrid, in combination with an atmosphere giving off nitrogen.

In testimony whereof I affix my signature in presence of two witnesses.

EMIL PODSZUS.
